COMBINED RECEPTACLE AND ROLLER FOR A PAINT METERING DEVICE

Edward H. Meisner, Dumont, N.J., assignor to
Red Devil Inc., Union, N.J.

Filed Jan. 17, 1972, Ser. No. 218,640

Term of patent 14 years

Int. Cl. D8—05

U.S. Cl. D64—18

FIG. 1

FIG. 3

FIG. 2

FIG. 4

FIG. 5

FIG. 6

FIG. 1 is an exploded perspective view of a combined receptacle and roller for a paint metering device showing my new design;

FIG. 2 is a side elevational view of the paint metering roller, with the receptacle being omitted for ease of illustration;

FIG. 3 is a top plan view thereof;

FIG. 4 is a front elevational view thereof;

FIG. 5 is a side elevational view thereof; and

FIG. 6 is an isometric bottom plan view thereof.

I claim:

The ornamental design for a combined receptacle and roller for a paint metering device, substantially as shown.
